UNITED STATES PATENT OFFICE.

WILLIAM A. SCHLEICHER, OF CLEVELAND, OHIO, ASSIGNOR TO THE EBERHARD MANUFACTURING COMPANY, OF CLEVELAND, OHIO, A CORPORATION OF OHIO.

PROCESS OF MAKING SWIVELS.

Original application filed August 16, 1921, Serial No. 492,741. Divided and this application filed November 15, 1922. Serial No. 601,075.

To all whom it may concern:

Be it known that I, WILLIAM A. SCHLEICHER, a citizen of the United States, residing at Cleveland, in the county of Cuyahoga and State of Ohio, have invented a new and useful Improvement in Processes of Making Swivels, of which the following is a full, clear, and exact description.

The present invention relates broadly to 10 swivels of general utility and to a process of making the same, and more particularly to a swivel construction comprising members having an efficient bearing therebetween and of such shape that the manufacture thereof 15 is facilitated.

At the present time, it is quite general practice to form swivels of different constructions and adapted for different purposes by casting one of the swivel members 20 around the other, using one of the members as a core for the casting. This practice in many instances results in fusion of the metal at the joint thereby rigidly connecting the members and rendering the product useless 25 as a swivel.

It is also old to construct articles of this nature by first forming separate members adapted to be interfitted to produce the completed swivel. The process of making such 30 articles has, however, usually required a heating, forging and/or welding operation which is objectionable. Articles made by this method have also ordinarily had interfitting grooves and shoulders requiring special tools for their formation and increasing 35 the friction surface between the members.

I am also aware that swivels have been constructed by inserting a portion of the member within the barrel of the female 40 member and then striking in portions of the barrel to hold the members in assembled position. Also, I am aware that swivels have been formed by providing an eye member having ears thereon which are turned 45 down toward each other about the body of the male member.

The foregoing methods have involved either the application of heat or the requirement of specially formed tools rendering 50 the entire process expensive and providing an article not possessing all of the desirable characteristics of strength, ease of rotation of the parts, and uniformity of product.

By the present invention there is provided

an improved method and article insuring 55 uniformity of product having the required strength, and capable of being inexpensively manufactured. The construction is such that the operation of the swivel does not produce any objectionable binding tendencies 60 and the use of heat in the assembly of the parts is obviated.

In the accompanying drawings there is shown, for purposes of illustration only, a preferred embodiment of the present invention, it being understood that the drawings do not define the limits of this invention and that changes may be made in the construction and operation disclosed therein without departing from the spirit and scope 70 of my broader claims.

In the drawings,

Figure 1 is a side elevation, partly in section and partly broken away, illustrating the two swivel members before assembling;

Fig. 2 is a similar view illustrating the members in assembled relation ready for the pressing operation, and

Fig. 3 is a view, similar to Fig. 2, showing a portion of a completed swivel.

The present application is a division of my application Serial No. 492,741, filed August 16, 1921.

In accordance with the present invention, a swivel embodying the desired characteristics may be formed by providing a female member 2, having formed therein an opening 3 of substantially uniform diameter throughout its entire length. The member 2 is also formed with a circumferentially extending groove 4 adapted to receive, retain and guide a suitable forming tool which may comprise dies A and B. The member 2 may have secured thereto or extending therefrom suitable means 5 enabling the swivel to be 95 operatively connected to the parts with which it is to be used.

Co-operating with the member 2 is a second member having formed thereon an enlarged head 6 provided with a tapered or 100 curved outer bearing surface 7 forming a bearing portion of reduced diameter. In Figure 1 the respective swivel members are illustrated before assembling. It will be apparent that by reason of the construction 105 of the respective members, they may be easily produced by casting as the the surfaces adapted for interfitting engagement

are free from flanges or grooves of angular cross section.

In Fig. 2, the respective members are illustrated in assembled relationship. For closing the member 2 about the bearing surface 7, there may be provided dies A and B having their operative faces shaped to engage and substantially conform to the external contour of the member 2. It will be apparent that by reason of the provision of the groove 4, and the corresponding bead or shoulder 8, the dies are positively received, retained and guided as they are moved inwardly, thereby enabling the member 2 to be accurately compressed around the head 6 and bearing surface 7 to provide a swivel connection operating with a minimum of friction. Unless the groove 4 is provided, as described, it has been found impossible to control the tools and press them in the comparatively large body of the casting in such manner as to form a satisfactory joint between the two members.

The reduced beveled portion of the head 6 positively prevents the members from being pulled apart. After the parts are assembled in the manner set forth, and as clearly indicated in Fig. 3, the bearing surface 7 permits easy rotation of one of the members with respect to the other and the swivel is therefore adapted to take the place of similar articles as heretofore constructed.

The advantages of the present invention arise from the uniformity of product produced by carrying out the improved method whereby a perfect swivel joint is insured, and from the ease of manufacture without the use of heat or complicated machining and interfitting operations.

40 I claim:

1. The method of making swivels, comprising providing a member having an opening therethrough and formed with a tool-controlling means, providing a second member having a head thereon, placing the said head within said opening, and then partially closing the opening to cause the walls thereof to engage said head by utilizing said means to receive, retain and guide a forming tool, substantially as described.

2. The method of making swivels, com-

prising providing a member having an opening therethrough and formed with a circumferentially extending tool controlling groove around said opening, providing a second member having a head thereon, placing said head within said opening and then partially closing said opening to bring the walls thereof into engagement with the head by utilizing said groove to receive, retain and guide a forming tool, substantially as described.

3. The method of making swivels, comprising providing a member having an opening therethrough and formed with a circumferential tool controlling groove, providing a second member having a reduced portion thereon, placing said reduced portion within said opening, and then partially closing said opening to cause the walls thereof to engage said portion by utilizing said groove to receive, retain and guide a forming tool, substantially as described.

4. The method of making swivels, comprising providing a member having an opening therethrough and formed with a circumferentially extending tool controlling groove forming a shoulder on one end of said member, providing a second member having a head thereon, with a reduced bearing portion, placing said head within said opening, and then partially closing said opening by engaging said groove with suitable tools to cause the walls of said opening to engage the reduced portion on the second member, substantially as described.

5. The method of making swivels, comprising providing a member having an opening therethrough of substantially uniform diameter throughout its length and having an external circumferentially extending tool controlling groove, providing a second member having a head thereon with a reduced bearing portion, placing said head within said opening, and then partially closing said opening by engaging said groove with suitable tools to cause the walls of said opening to engage the reduced portion on the second member, substantially as described.

In testimony whereof I have hereunto set my hand.

WILLIAM A. SCHLEICHER.
